Z. KINSEY,

Packing Sheet Lead,

N° 23,031.

Patented Feb. 22, 1859

UNITED STATES PATENT OFFICE.

ZEBULON KINSEY, OF DUBUQUE, IOWA.

IMPROVEMENT IN PACKING BAR-LEAD.

Specification forming part of Letters Patent No. 23,031, dated February 22, 1859.

To all whom it may concern:

Be it known that I, ZEBULON KINSEY, of Dubuque, Dubuque county, State of Iowa, have invented a new and improved method of putting up packages of cast or wrought bars, pigs or ingots of lead, tin, zinc, or other metal; and I do hereby declare that the following is a full and exact description thereof, reference being had to the accompanying drawing, and to the letters of reference marked thereon.

First. I prepare a bar or bolt in the form substantially of that marked B in the drawing, having at one end a head, (see H,) and at the other end a slit. (See K.)

Second. I prepare the ingots which I wish to make up into packages with such perforations, or perforate them in such manner and place, that when several of them are laid together the perforations are brought in juxtaposition.

The drawing marked C represents an ingot with perforations near each end, marked S.

Third. To make up the package I pass the

said bolt into the perforations of as many ingots as I wish in one bundle, pressing it home to the head, holding the package firmly in this position. I open the end of the bolt at the slit K, and bend the respective halves in opposite directions, forcing them closely down upon the upper ingot. When this is done the package is complete and ready for transportation.

The drawing marked A is a representation of one form of such package.

What I claim, and desire to secure by Letters Patent, is—

The use of the bar or bolt B, made substantially as described, when inserted in perforations made in bars or ingots, and clinched or fastened in the manner substantially and for the purpose aforesaid.

Dubuque, January 31, 1859.

ZEBULON KINSEY.
